UNITED STATES PATENT OFFICE.

ROBERT SAFFORD McINTYRE, OF RIVERSIDE, CALIFORNIA.

DESIGN FOR A TREE-PROP.

SPECIFICATION forming part of Design No. 35,265, dated November 5, 1901.

Application filed August 19, 1901. Serial No. 72,611. Term of patent 7 years.

To all whom it may concern:

Be it known that I, ROBERT SAFFORD MCINTYRE, a citizen of the United States, and a resident of Riverside, in the county of Riverside and State of California, have invented and produced a new and original Design for a Tree-Prop, of which the following is a specification, reference being had to the accompanying drawings, forming a part thereof.

10 Figure 1 is a side view of a prop embodying my design. Fig. 2 is a front view, and Fig. 3 is a sectional plan, on the line 3 3 of Fig. 1.

The design comprises a shank *a*, terminating at one end in a curved saddle-like member *b*. In the shank *a* appears a longitudinal slot *c*, having parallel side walls, and the side portions of the shank are bent longitudi-

nally in the lines of said side walls of the slot *c* to form diagonally-disposed outwardly-projecting flanges *d*, running the full length of the shank and extending into the saddle-like member *b*. At each end of the slot *c* appears a diagonally-standing spur *c'*.

Having thus described my invention, what I claim as new, and desire to secure by Letters Patent, is—

The design for a tree-prop, as herein shown and described.

In testimony whereof I have signed my name to this specification in the presence of two subscribing witnesses.

ROBERT SAFFORD MCINTYRE.
